UNITED STATES PATENT OFFICE

JULIUS B. WANTZ, OF OAK PARK, ILLINOIS, ASSIGNOR TO GENERAL ELECTRIC X-RAY CORPORATION, OF CHICAGO, ILLINOIS, A CORPORATION OF NEW YORK

X-RAY APPARATUS

Application filed January 5, 1928. Serial No. 244,592.

The present invention has primarily to do with an X-ray apparatus. It relates particularly to an auxiliary or ancillary apparatus or control device whereby it is possible to convert the conventional X-ray apparatus into an instrumentality which may be instantly changed from capacity for radiographic work to adaptability for fluoroscopic work, and vice versa.

10 Included in the objects of the invention, are the following:

A device to be attached to and made a part of the conventional X-ray apparatus whereby the apparatus is adapted to take radiographic pictures or to be used for fluoroscopic examination;

An instrumentality to be made a part of the usual X-ray apparatus whereby such apparatus is converted into a device capable of 20 maintaining one setting for radiographic work and another setting for fluoroscopic examinations, the settings for each being adjustable, but the adjustment of one having no effect upon the adjustment of the 25 other;

The combination with a radiographic apparatus of switch means and a control therefore for whereby such apparatus is converted into a device for making fluoroscopic examinations 30 without the adjustment of the radiographic settings, such device being capable of instant reconversion into an apparatus for taking radiographic pictures;

Means for converting an X-ray equipment 35 arranged for radiographic exposures into an apparatus for fluoroscopic examination, such means permitting of separate and independent adjustments with respect to photography and fluoroscopy; and

40 A new article of manufacture comprising switch means and control members therefor formed into a unit and adapted to be made a part of or attached to a conventional X-ray circuit whereby such circuit instantly becomes convertible from a radiographic apparatus to one for fluoroscopic examination, or vice versa.

These, and such other objects as may hereinafter appear, are obtained by the novel 50 construction of the various parts employed,

by the combination of such parts one with another, and by the arrangement of the several elements which constitute the apparatus.

The invention is illustrated in three sheets of drawings accompanying this application 55 and in such drawings, one of which is schematic or diagrammatic, the conventional circuit for a radiographic apparatus having in association therewith an automatic timer of conventional design and a circuit breaker is 60 shown.

In the drawings:

Figure 1 is an assembly of the control stand, a conventional foot switch, and a hand switch used in the invention, the elements 65 being in part in section and in part in elevation;

Figure 2 is a plan view of foot switches in the control stand of the apparatus;

Figure 3 is a plan view of the auto-transformer control and adjacent parts within the 70 control stand;

Figure 4 is a section through a portion of the casing and showing the filament current control forming a part of the stand in 75 elevation; and

Figure 5 is a schematic diagram of the apparatus and the circuits employed therewith.

This application is a continuation in part 80 of an application of Julius B. Wantz, serially numbered 167,496, entitled X-ray apparatus and filed February 11, 1927.

In the practice of the invention, it is usual and customary to house the several switches 85 for bringing the auxiliary apparatus into operation, the auxiliary filament current control means, and the auxiliary high tension control means in a stand having two casings, the lower thereof holding such switches and 90 having projecting therefrom pedals adapted to be actuated by an operator's foot, as is shown at the base of Figure 1 and in Figure 2. The auxiliary filament control and the auxiliary auto transformer are disposed in a casing 95 at the top of a pedestal projecting upwardly from the lower casing.

The entire apparatus is portable in its nature and is adapted to be shifted about a laboratory or X-ray examination room so that 100

it may be placed in the most convenient location that the objects in view may be accomplished.

Like reference characters are used to designate similar parts in the drawings and in the description of the invention which follows.

Reference should now be had to Figure 1. The stand hereinabove referred to comprises a base A which is a housing for the switches 10 adapted to bring the auxiliary autotransformer 41 and the auxiliary filament current regulator 42 into play. These switches are further illustrated in Figures 2 and 5.

Upwardly extending from base A is a standard B at the top of which is a housing C in which is disposed an auxiliary auto transformer D of conventional design and controlled by rotatable handle E, and filament current transformer control member F also 20 of conventional design and regulated by the control handle G. Figure 3 is a plan view of the contact board H and of the control handle and adjacent parts used in housing C and covering a part of the structure of auto transformer D, leaving exposed contacts I of said auto transformer. Figure 4 further discloses the structure of the filament transformer control member F.

All of these parts and members except the 30 housings and pedestal will be found in and readily recognized in Figure 5.

In said figure a conventional wiring system for an X-ray apparatus for a tube of the hot cathode type is disclosed except in so 35 far as that system is modified to accommodate the present invention. The invention, of course, may be adapted for use with gas tubes with certain changes.

In such a wiring system as is disclosed in 40 Figure 5, conduits (see lower right hand corner) from an alternating current power line are connected to a main auto transformer 12, which main auto transformer may be disposed in a main control stand, not shown but 45 of any conventional design, where handles or other means are provided for its operation and adjustment. Control stands are common in the art and generally include switches, auto transformer fuses, and other equipment, such 50 for example as transformers, all within a vertical container, and having operating handles conveniently located with respect thereto.

From the main auto transformer 12, conduits are arranged to run to the primary of a 55 high voltage transformer 31. The secondary of such high voltage transformer is adapted to be connected directly to a self rectifying tube or to a rectifier where a self rectifying type of X-ray tube is not employed.

Usually, the alternating current line feeds 60 to the main auto transformer a current at a voltage of 220 volts. In addition to such alternating current line, (see upper left hand corner of drawings), a separate alternating current line of 110 volts is connected to a

filament current transformer, which latter apparatus is marked 32 in the drawings.

In circuit with such alternating current line and filament current transformer 32 is a filament current regulator 33, such as is conventional in the X-ray art. The secondary current from the filament current transformer 32, which is a step-down transformer, is used to heat the filament of the X-ray tube used in the apparatus. Other methods for controlling electron emission may be substituted for that described without departing from the spirit of the invention.

The same alternating current line, (or another, preferably of 110 volts) is used for actuating a circuit breaker marked 34 in the drawings. In connection with such circuit breaker is an automatic timer, the device here disclosed being more or less conventional and comprising means for timing exposures when radiographic work is being carried on with the apparatus. Such timer is marked 35 in the drawings.

Such apparatus usually comprises a motor driven mechanism for carrying spaced electrical contacts which contacts, when brought together, provide circuits for selectively energizing the circuit breaker 34. A solenoid for controlling a clutch whereby the power of the motor is made available for operating such contacts is a usual and customary part of the timer apparatus. Timer devices are common to the industry but a more complete description is here given.

As hereinabove indicated, there may be disposed in housing A, which may comprise any suitable box-like metallic or other desirable structure, a plurality of switches, indicated in the drawings, by the ordinals 1, 2, 3, 4, 5, and 6. The normal position of the blade portions of each of these switches is "up" with respect to the circuits shown in the diagram. The switches 2 to 6 are normally in contact with the contacts shown above the switch blades. The structure of the blades, the contacts, the foot pedals, and the spring members employed therein are shown clearly in Figures 1 and 2.

When it is desired to operate the device for radiographic exposures, the blades of switches 1 and 2 are pressed downwardly. This action disconnects the switch member 2 from the contact it normally engages and also provides for the impinging of the switch blades of switches 1 and 2 upon the contacts shown beneath the blades of said switches.

The contacts are made in the order indicated in the drawings, that is, the circuit closed by switch 1 is established before the circuit including switch 2 is closed. The two switches are adapted to be actuated by a single foot pedal 36 mounted in the casing A. In the normal position of such pedal, the switches 1 and 2 are "up", and in depressed position, said switches are "down".

For fluoroscopic work the blades of switches 3, 4, 5, and 6 are pressed downwardly. This may be done with another pedal 37. Movement of such other pedal 5 provides an immediate "disconnect" with respect to switch 5 and 6, followed by a later "disconnect" of switches 3 and 4.

New circuits are thereafter established through switches 5 and 6 in advance of the 10 connection to be established through switch 3 by continued and further pressure upon the foot pedal 37 which controls said switches 3, 4, 5, and 6. No new circuit is established through switch 4.

15 In the timer 35 is a terminal "S" which is electrically connected to the knife blade of switch 1. Said knife blade makes contact only when pressed downwardly. When pressed downwardly, electrical connection 20 from terminal "S" is established through said switch in a manner later indicated.

Normally, the knife blade of switch 2 is in connection with the conduit connected to another terminal 8 in the timer. When pressed downwardly, such connection is broken. After the circuit formed by the actuation of 25 switch 1 has been established, a second circuit is established by further downward pressure of the pedal through switch 2 between said terminal "S", the knife switch 1, the knife switch 2, the knife switch 3 (which remains undisturbed in its upper position), and a conduit leading back to a terminal 9 upon said 30 time switch.

35 The effect of such connections is to establish a plurality of circuits whereby the time switch or timer 35 is set in operation. The solenoid referred to above is thus actuated to operate the clutch controlled thereby.

40 In the less modern time switches, the motor is put into operation only immediately anterior to the time a radiographic exposure is to be made. In the present apparatus, the 45 circuits in the time switch are arranged to provide for the continuous operation of the motor. In this manner, the device is kept in condition for instant use for timed radiographs without any necessity for the operator leaving 50 the position occupied by him for fluoroscopic examination. Said time switch 35 through the agency of the circuit breaker 34, causes current to flow to the rectifier or tube, as the case may be, through the main auto transformer and the high voltage transformer 55 whereby radiographic current, the voltage of which is determined by the settings of the main autotransformer, is impressed upon the tube terminals.

60 It is to be noted at this time that the switch 4 is also up so that the auxiliary filament current control is inoperative and likewise the switches 5 and 6 are up so that the auxiliary autotransformer likewise is inoperative or 65 out of circuit.

For the purpose of maintaining the set-

tings desired for radiographic work and concurrently using the apparatus for fluoroscopic work, the utility of the invention now becomes apparent. It has already been stated that a second foot pedal 37 is adapted to actuate switches 3, 4, 5, and 6. Switch 2 is normally disposed in its uppermost position as is switch 3, hence there is through said switches a closed circuit intermediate the terminal 8 and the terminal 9 of the time switch.

70 The first effect of pressure upon the second foot pedal 37 is to disconnect switches 5 and 6 whereby the circuits intermediate the main autotransformer are broken. Further movement downwardly of said foot pedal disconnects switch 4 from the contact therefor and puts in circuit with the alternating current line to the filament current transformer the auxiliary filament current control which control is used for the purpose of reducing the 75 electromotive force impressed upon the cathode of the X-ray tube.

Concurrently with putting in circuit the auxiliary filament current control, the circuit intermediate the terminals 8 and 9 of the 80 timer is broken by the opening of the switch 3 at its upper contact.

Further downward pressure causes the knife blades of switches 5 and 6 to establish connections with the lower contacts shown 85 whereby to put into circuit the auxiliary autotransformer so that the voltage transformer is reduced to that necessary in an X-ray tube to adapt it for fluoroscopic examinations.

90 Still further downward pressure causes the knife blade 3 to contact with the lower contact in association therewith, thereby creating a circuit to the circuit breaker and its "on" solenoid. By further pressure, there is a 95 new circuit established between the terminals, the source of electromotive force, and the "on" solenoid of the circuit breaker. This connection renders inoperative the timing element in said time switch and causes the circuit breaker to remain in closed position so long as pressure is applied to such foot pedal.

100 Release of the foot pedal 37 causes the re-establishment of the circuit to the "off" solenoid of the device so that electromotive force 105 to the tube is cut out and such change adapts the device to radiographic work and concurrently renders it operable so that it is adapted to be actuated by downward pressure upon the foot pedal controlling switches 1 and 2.

110 Through the agency of switches 1 and 2, the circuit to the solenoid so broken may be reestablished. When so established, however the timing element is in operation and the contact is for a predetermined period.

115 It should be instantly perceivable that the device is adapted to be applied to a single tube so as to give to it a double utility. The invention is such that the proper adjustments 120 of the main filament regulator and of the 125

main autotransformer are maintained for the production of X-ray photographs while an operator is employing the tube with a lower voltage for the purpose of making fluoroscopic examinations.

In use, the proper position for a radiographic exposure may be located by a fluoroscopic examination. This is done with switches 3, 4, 5, and 6 down. When such position is found, the operator may release the pedal controlling said switches 3, 4, 5, and 6, insert a cassette into a holder therefor forming a part of the apparatus (not shown) which is used in conjunction with the patient under examination.

The operator may then press the other foot pedal which controls switches 1 and 2 to obtain a radiographic exposure.

The adaptability of the device is such that 20 the operator may maintain two working adjustments at all times and thus obtain expeditiously photographs while determining in advance whether the patient is so disposed as to provided for a good exposure.

25 In association with the circuit intermediate the main auto transformer and the primary of the high voltage transformer, is the usual hand operated X-ray switch which renders the apparatus usable independently of 30 the circuit breaker. Such hand operated switch is marked 15.

In connection with the timer, there is also 35 provided the regular timer foot switch 39, Figures 1 and 5, whereby the timer may be operated by the foot wholly independently of the device forming the subject matter of this invention, but only when the device here described is out of circuit.

Reference should again be had to Figure 40 5 which is a schematic layout of the wiring circuit employed in carrying out the invention, and a partially diagrammatic representation of the timer and circuit breaker.

The alternating current line at the upper 45 left hand part of the figure supplies electro-motive force to the circuit breaker, filament current transformer, and the timer.

In association with the circuits leading to 50 these several elements, said alternating current line there is a hand switch 38, which has two operable positions, "regular", which would be the upper position in Figure 5, and "fluorographic", which would be the lower position in Figure 5.

55 There is associated with the arrangement of circuits a circuit breaker 34, comprising an armature which is adapted to be moved to the right or left in Figure 5 by the solenoids at the right and left of the circuit breaker as illustrated, and marked "on" and "off". Said circuit breaker at its top and bottom in the illustration has two bars, hereinafter called an upper connector and a lower connector bar, and these bars are adapted 60 by the actuation of and with the armature to move relatively to a plurality of fixed contacts.

70 In connection with such fixed contacts, it is proper to say that the upper left hand contact, and hereinafter so designated, never is

out of sliding engagement with the upper connector bar and that the lower right hand contact, so designated hereinafter, never disengages itself from the lower connector bar.

75 The cross bar of the circuit breaker is a conductor insulated from the upper and lower connector members, just described, and moves with the armature which projects through the "on" and "off" solenoids. When the circuit breaker is in its right hand position, it is adapted to establish connections between the contacts forming a part of the circuit to the primary of the high voltage transformer.

80 The timer herein depicted schematically in part is of a well known commercial type, as has already been pointed out, which, however, must be slightly modified as to the circuits thereinto for use in this apparatus, but it is mechanically unchanged. Such timer 35 is actuated by a constantly running motor, marked 40, which motor is geared to operate a disk 20 shown partly in the form of gearing and partly in dotted lines in the figure.

85 In association with such geared disk is a disk 21 in full lines, which carries an arm 22, said disk 21 comprising one side of a clutch which is adapted to engage the geared disk 20, the other side of the clutch, and be moved by the geared disk 20 whenever pushed into such engagement by a lever 23 pivoted at 24, actuated by the timer solenoid shown therebeneath and so identified. Any suitable means may be provided to cause the disk 21 to return to its normal position, that in which shown, whenever the disks 20 and 21 are separated.

90 The timer itself comprises two plates, 25 and 26, one insulated from the other, but which, however, may only be moved in unison. The outer of said plates 25 is provided with a contact 27 and the other plate 26 with an adjacent contact 28, the two contacts 27 and 28 being adapted to be forced into impinging relation as an incident to contact 27 being struck by the arm 22 disposed upon the movable disk 21. Each of said plates 25 and 26 has terminal contacts 9 and 8, respectively, which are in sliding contact therewith at all times.

95 Within the timer are contacts 29 and 30 which are adapted to be kept in closed relation by arm 22 resting thereagainst, and during all of the time which said arm 22 is not traveling toward the pair of contacts 27 and 28 upon the plates 25 and 26 just referred to. It will be noted that contact 29 is spring actuated to cause it to separate from contact 30 when the urging influence of arm 22 is removed.

Said plate 21 and the arm 22 actuated thereby, as already stated, is provided with any suitable mechanism whereby they will return instantly to their normal position upon

5 the timer solenoid being de-energized which allows the clutch to disengage, the force of the spring actuating disk 21 being necessarily greater than that in contact 29.

10 The circuits will be first described with the hand switch in its regular position with its blades in engagement with the upper contacts.

15 In such position, the device is intended only for radiographic exposures of the regular order and of a time determined by the angular position of the two plates 25 and 26 in the timer, that is, how far the contacts 27 and 28 therein are removed from the normal position of the arm 22, for the arm 22 when 20 actuated by the timer motor while the solenoid actuates the clutch (plates 20 and 21) moves at a constant and fixed speed toward the contacts 27 and 28. The radiographic exposure extends for that period of time during 25 which said arm 22 is traveling from its normal and illustrated position until it impinges the lowermost of contacts 27 and 28, whereby to cause said contacts to engage one another.

30 The circuits are traced and are as follows:

A circuit from the upper left hand alternating current line to the motor of the timer, is used to energize said motor, the circuit being from the left hand conduit of the alternating current line to the timer motor switch, to the motor, and from the motor to the right hand conduit of the alternating current line.

35 A circuit is from the left hand conduit of the alternating current line at the left and top of the figure to the centre of the hand switch 38 and from the centre of said switch to the foot switch 39, from the foot switch back to the hand switch 38 and from thence to the right hand upper contact of the circuit breaker which is in contact with the upper contact bar only when the tube is being energized. In this described position, no current 40 can flow to the X-ray tube, and the X-ray tube is inactive.

45 50 If the foot switch 39 is closed, then the circuit becomes, from the left hand conduit of the alternating current line to the center of the hand switch 38, to one contact in the foot switch 39, to the cross bar therein, the other contact in said switch, back to the left side of the hand switch 38, and from thence to the terminal "S" on the timer solenoid, through the said solenoid, terminal 11 and back to the right hand conduit of the alternating current 55 line.

60 At the same time, the foot switch 39 closes a circuit from the left side of the hand switch 38 to terminal 10 and contact 30, which contact through contact 29 establishes one circuit 65 to the left lower contact of the circuit break-

er, from whence for an instant a circuit through the "on" solenoid of the breaker to the right hand alternating current conduit is established.

Another circuit from said line, as has been 70 pointed out, energizes the filament transformer, and also the auxiliary filament regulator 42, when the latter is in circuit.

75 Another circuit from said alternating current line, as previously indicated, runs from the right hand conduit to the "on" solenoid of the circuit breaker 34, and from thence to the lowermost right hand contact therein, the lower connector bar, the lower left hand contact therein, to the timer, through the contacts 29 and 30, to the hand operated switch 38 so that in the course of the actuation of the circuit breaker there is at least an instant impression of current through the right hand 80 "on" solenoid when the foot switch 39 is closed, which impression is sufficient to force the cross-bar to the right to close the circuit to the high tension transformer as has heretofore been pointed out.

85 The "off" solenoid of the circuit breaker 34 is energized by a conduit from the right hand conduit of the alternating current line, and the circuit back to the left hand conduit of said line is through the upper left contact in the circuit breaker, the upper connector bar, 90 the upper right contact, the right side of the hand switch 38, through the foot switch 39, in open position, back to the hand switch 38 and to the left hand conduit in the alternating current line. Thus, releasing the foot switch 39 with the hand switch 38 in "regular" position 95 instantly shuts off the electromotive force energizing the high tension transformer.

100 This would be true even if the time switch was still in movement and had not reached the limit of its travel. Such a measure is necessary in order that the operator may terminate a radiographic exposure if spoiled, or the patient being nervous or fidgety approaches too closely to the high tension conduits.

105 The "off" circuit established in the manner just indicated is an instant circuit, for such circuit is broken as an incident to the armature in the circuit breaker moving to the left.

110 When the time switch shall have reached the limit of any setting, the "breaking" circuit is from the right hand conduit of the alternating current line to the "off" solenoid of the circuit breaker, the upper left contact therein, the upper connector bar, the upper right hand contact therein, the terminal 8, the disk 26, the contact 28, the contact 27, the plate 25, the terminal post 9 of said timer, and the left hand conduit of the alternating current line.

115 120 From the circuits described, it is manifest that the timer is put in operation upon the foot switch being closed. The cycle of operations which occur after said switch has been 125

closed will now be further described. The instant that the timer is placed in operation, the "on" solenoid of the circuit breaker is energized, but immediately thereafter the 5 arm 22 ceases to cause the contacts 29 and 30 to impinge, thus opening the circuit to the right hand solenoid of the circuit breaker so that the "off" solenoid or timer "breaking" circuit may become effective. The cross 10 bar of the circuit breaker remains in contact with the main contacts therein completing and maintaining the circuit to the high tension transformer until the "off" solenoid is energized to break such circuit to the high 15 tension transformer.

Such circuit is broken when the foot switch is released or the arm 22 impinges contact 27 to force the latter against contact 28 when circuits to the "off" solenoid are established. 20 These circuits have already been described. The circuit is an instantaneous one for the movement of the armature of the circuit breaker to the left opens both of said circuits.

25 Thus the timer acts first to establish a closed circuit to the high tension transformer by moving the cross member in the circuit breaker to the right. The impression of the current upon the "on" solenoid to accomplish 30 this is instant, and the impression of current upon said solenoid must be instantly terminated not to interfere with the timer or foot switch. Time exposures of 1/20 or less of a second are sometimes desired.

35 By changing the position of the hand switch from "regular" to "fluorographic", the foot switch 39 becomes inoperative, and the device forming the subject matter of this application for Letters Patent, in part, be- 40 comes a part of the circuit.

When the fluorographic unit is in circuit and when switches 1 and 2 are in normal position the circuit is from the left hand conduit of the alternating current line, to the 45 hand switch, from the hand switch to switch 3, from said switch to switch 2, which is normally in its uppermost position, to the hand switch, and from the hand switch to the right upper circuit breaker contact. The current 50 cannot go beyond this point.

When switches 1 and 2 are pressed downwardly, the circuits then become the left hand conduit of the alternating current line to the hand switch 38, to switch 3 and from its upper 55 contact to switch 2, which now engages its lower contact, and from thence to switch 1, whereby the solenoid is brought into operation, the line back to source of power being from terminal 11 to the right hand conduit. 60 The circuit from switch 1 continues to the hand switch 38 and from thence to contact 30, to contact 29, to the circuit breaker and to the right hand solenoid therein, and from thence to the other side or right hand conduit 65 of the alternating current line. It is to be

noted that the time of contact in switches 1 and 2 is different, the contact with 2 being established after switch 1 is closed. This provides for the positive actuation of the circuit breaker at the instant that the solenoid is rendered operative, the time required for the timer solenoid to operate the clutch in the timer (plates 20 and 21) being sufficient to permit the circuit breaker to be thrown to "on" before the contacts 29 and 30 are separated. 70

The operation of the device is now the same as if the foot switch were employed, the circuit being different, however, as has been indicated, so as to bring into convenient instant use additional switches whereby a fluorographic current may be brought about and controlling in the same apparatus as the radiographic current. 80

1 claim:

An X-ray apparatus comprising an X-ray tube, a filamentary cathode and anode in said tube, a high tension transformer connected thereto, a main auto-transformer for regulating the voltage impressed upon the high tension transformer, a circuit intermediate said high tension transformer and said auto transformer and adapted to be closed by a circuit breaker, an additional auto-transformer for regulating the voltage impressed upon said high tension transformer and adapted to displace said main auto transformer, switch means for connecting and disconnecting said additional auto-transformer to said high tension transformer, a filament current transformer for said tube, a filament current regulator governing the electromotive force impressed upon said filament current transformer, an additional filament current control means for said filament current transformer, a circuit for connecting said filament current regulator and said additional filament current control means, switch means being unitary with said first named switch means for controlling said filamentary circuit, a timer adapted to determine the time during which high tension current may be impressed upon said X-ray tube, a circuit breaker in combination with said timer and adapted to close said first named circuit, switch means for said timer whereby the timing element thereof is rendered operable or inoperable relatively to said circuit breaker, and means for selectively actuating said first named switch means to produce a relatively powerful or weaker X-light for a predetermined period of time. 100 105 110 115 120
